Filed Dec. 19, 1974, Ser. No. 534,571

Term of patent 14 years

Int. Cl. D2—02

U.S. Cl. D2—227

The figure is a front perspective view of an apron showing my new design with the applique in opened condition. The rear of the apron is identical to the front except that it is plain and unornamented.

I claim:

The ornamental design for an apron, as shown and described.
